United States Patent Office

Des. 184,656
Patented Mar. 24, 1959

184,656

AIRCRAFT SEAT

Leslie Everett Baynes, Langley Aerodrome, England, assignor to Baynes Aircraft Interiors Limited, Langley Aerodrome, England, a British company

Application May 20, 1957, Serial No. 46,251

Term of patent 14 years

(Cl. D15—8)

Fig. 1.

Fig. 2.

Figure 1 is a front perspective view of an aircraft seat showing my new design as it appears from above and one side; and

Figure 2 is a back perspective view from above and the other side.

I claim:

The ornamental design for an aircraft seat, as shown.
